Patented Dec. 25, 1973

229,661

MOBILE COOKING CART

Theodore C. Lambertson, 1369 Rollins Road,
Burlingame, Calif. 94010

Filed Oct. 13, 1971, Ser. No. 189,068

Term of patent 14 years

Int. Cl. D7—02

U.S. Cl. D7—108

FIG. 2

FIG. 3

FIG. 4

FIG. 5

FIG. 6

FIG. 1 is a view in perspective of a mobile cooking cart showing the features of my new design;

FIG. 2 is a front view in elevation of the same;

FIG. 3 is a top view of the same;

FIG. 4 is a rear view in elevation of the same;

FIG. 5 is a right side view in elevation of the same; and

FIG. 6 is a left side view in elevation of the same.

I claim:

The ornamental design for a mobile cooking cart, substantially as shown and described.
